ATTORNEY

UNITED STATES PATENT OFFICE.

DOUGLAS SETTLE, OF SAN DIEGO, CALIFORNIA.

KEY CONTAINER.

Application filed August 10, 1927. Serial No. 212,037.

This invention relates to improvements in key containers, an object being to provide a device for conveniently holding a number of keys, and thus reduce to a minimum, danger 5 of loss.

Another object of the invention is the provision of a device of this character having means by which the keys may be readily attached or removed, the construction being 10 such as to permit of the device being conveniently carried in the pocket.

With the above and other objects in view, the invention further includes the following 15 novel features and details of construction, to be hereinafter more fully described, illustrated in the accompanying drawings and pointed out in the appended claims.

In the drawings:—

Figure 1 is a side elevation of the invention showing a key extended at each end of the container and also showing by dotted lines the position of the movable plate when inserting or removing a key.

Figure 2 is an edge view of the invention. 25 Figure 3 is an enlarged transverse sectional view.

Figure 4 is a perspective view of the invention with the parts separated.

Referring to the drawings in detail where- 30 in like characters of reference denote corresponding parts, the reference characters 10 and 11 indicate a pair of spring plates, the plate 10 being hereinafter referred to as the rigid plate and the plate 11 as the movable plate.

The plate 10 is provided centrally of its length with a rectangular opening 12, which is adapted to receive the rectangular reduced end 13 of a spacing member 14. The reduced end 13 of the member 14 is inserted 40 within the opening 12 and this end is then riveted or upset as shown at 15 in Figure 3 of the drawings. The member 14 and plate 10 are thus rigidly connected. The plate 10 is further provided at each end with an opening 16 and these openings receive the reduced ends of key posts 17, the said reduced ends being riveted or upset as indicated at 18, so that the plate 10 and posts 45 17 are rigidly connected.

The plate 11 is provided with a central opening 19 adapted to receive the reduced rounded end 20 of the member 14 and this end is upset as shown at 21, so that the plate

11 will be pivotally mounted upon the mem- 55 ber 14. One end of the plate 11 is provided with an elongated slot 22 which removably receives the free end of one of the posts 17 while the opposite end of the plate is pro- 60 vided with a similar slot 23 to receive the free end of the other post 17. As shown in Figure 2 of the drawings the plates 10 and 11 are slightly convex to increase their spring tension, the tendency being to force the ends of the plates inward or toward one 65 another so that the ends of the posts 17 will normally be positioned within the slots 22 and 23. The ends of the plates may be readily disengaged from the posts 17 for the purpose of removing or replacing keys 70 from or upon the posts.

It is preferred to provide the posts 17 with washers 24. These washers are adapted to be placed between the keys and form spacing washers. In addition, they also pro- 75 vide friction surfaces for frictional engagement with the keys, and these washers together with the plates 10 and 11 serve to yieldingly hold the keys against pivotal movement. The keys will thus remain be- 80 tween the plates, until manually removed.

Mounted upon one of the plates 17 is a relatively small plate 25. This plate pro- 85 vides means for conveniently attaching a chain to prevent loss of the container.

The invention is susceptible of various changes in its form, proportions and minor details of construction and the right is here- 90 in reserved to make such changes as properly fall within the scope of the appended claims.

Having described the invention what is claimed is:

1. A key container comprising a pair of spring plates, a spacing member extending 95 from and having one of its ends secured to one of the plates and its other end engaged with the other plate, and key posts at opposite ends of and secured to one of said plates and having a detachable connection with the 100 other of said plates.

2. A key container comprising a pair of spring plates, a spacing member extending from and having one of its ends secured to one of said plates and its other end having 105 a pivotal connection with the other plate, and key posts at opposite ends of and secured to one of said plates and having a

detachable connection with the other of said plates.

3. A key container comprising a pair of spring plates, a spacing member extending from and having one of its ends secured to one of the plates and its other end engaged with the other plate, and key posts at oppo-

site ends of and secured to one of said plates and having a detachable connection with the other of said plates and combined friction and spacing washers mounted upon the key posts.

In testimony whereof I affix my signature.
DOUGLAS SETTLE.
